UNITED STATES PATENT OFFICE.

WALTER P. HANSELL, OF PITTSBURG, PENNSYLVANIA.

DESIGN FOR A SOAP-BOX.

SPECIFICATION forming part of Design No. 17,056, dated January 11, 1887.

Application filed October 12, 1886. Serial No. 216,073. Term of patent 14 years.

To all whom it may concern:

Be it known that I, WALTER P. HANSELL, a citizen of the United States, residing at Pittsburgh, in the county of Allegheny and State of Pennsylvania, have invented and produced a new and original Design for a Soap-Box, of which the following is a specification, reference being had to the accompanying drawings, forming part thereof, and which represent, 10 in—

Figure 1, a soap-box made according to my design. Fig. 2 shows a vertical section of the same.

The box consists of a base part, *a*, having a 15 side cover, and a central case part, *b*, capped with an acorn-shaped cover, *c*.

The box may be made of any suitable material, each case part being provided with 20 ornaments consisting of stripes and figures of contrasting colors, which are alternately arranged—first one color, and the next a different color, and so on. The ornaments on the vertical case part are of the form and style of oblique or spiral stripes, while those on the 25 sides of the base part are of the form and style of diamonds arranged in parallel lines of contrasting colors, the top side of said base part being ornamented with contrasting colors ar-

ranged in circles around the bottom of the vertical central case part, as seen in Fig. 1. 30 These two case parts form a double box, each part forming a separate closure, in which one part constitutes the support for the top part.

I claim—

1. The design for a soap-box herein shown 35 and described, the same consisting of the box-base *a*, having a knobbed cover at one side, and the central case part, *b*, the latter being capped with an acorn-shaped cover, *c*, the said box-base and central case parts being provided 40 with ornaments of contrasting colors alternating with each other.

2. The design for a standing box herein shown and described, the same consisting of the base - box *a* and a vertical central case 45 part, *b*, having an acorn-shaped cover, *c*, the said central case part provided with oblique or spiral stripes of contrasting colors alternating with each other, and the box-case provided with contrasting colors arranged in 50 concentric circles and in diamond figures, and provided with a drawer-cover at one side.

WALTER P. HANSELL.
